BRACKET FOR A TURRET STANDPIPE

John T. Corley, Providence, R. I., assignor to
J. M. Baker Pattern Company, Inc., Providence,
R. I., a corporation of Rhode Island

Application March 5, 1929, Serial No. 344,337
Renewed May 26, 1933

10 Claims. (Cl. 299—73)

This application is a continuation in part of copending application Serial No. 240,293, filed December 15, 1927, which matured into Patent No. 1,738,421, granted December 3, 1929.

5 This invention relates to a mounting for a portable turret standpipe; and has for its object to provide a bracket support for the standpipe, which bracket may be secured to a flat or plain surface or to a post or other cylindrical construction as may be convenient.

10 A further object of the invention is to provide a bracket with cooperating portions between the portable standpipe and the bracket so that the standpipe may be easily and quickly positioned and held secure in the bracket and yet be easily and quickly removed therefrom.

15 With these and other objects in view, the invention consists of certain novel features of construction, as will be more fully described, and particularly pointed out in the appended claims.

20 In the accompanying drawings:

Fig. 1 is a top plan view of a turret standpipe mounted in the bracket, the two parts of which are secured to a convenient board or plate.

25 Fig. 2 is a side elevation of the construction shown in Fig. 1.

Fig. 3 is a sectional view on line 3—3 of Fig. 1.

Fig. 4 is a perspective view of one part of the bracket.

30 Fig. 5 is a perspective view of another part of the bracket both of which in use are secured to some adjacent parts to cause them to function together.

Fig. 6 is a sectional view on substantially line 35 6—6 of Fig. 5 thru the spring pin with the portion of the turret standpipe shown in its relation to this part of the bracket.

Fig. 7 is a top plan view of a modified construction of bracket with the turret standpipe 40 mounted therein.

Fig. 8 is a side elevation thereof.

Fig. 9 is a side elevation of the turret standpipe shown in Fig. 7, removed from the bracket.

Fig. 10 is a perspective view of the bracket.

45 Fig. 11 is a sectional view thru the turret standpipe showing its relation to one part of the bracket.

Fig. 12 is an elevation partly in section thru the other part of the bracket.

50 Fig. 13 is a fragmental top plan view showing a modified construction with a clamp portion of the bracket secured to a different portion of the standpipe.

Fig. 14 is a side elevation showing the bracket 55 as secured to a pipe or post as distinguished from

a flat surface as illustrated in the preceding figures.

Fig. 15 is a side elevation of a detail showing the cooperating part for securing the bracket to the post illustrated in Fig. 14.

5 In the manipulation of a turret standpipe for fighting fires, it is found of advantage to provide a support for the standpipe so that the nozzle may be manipulated to direct the stream of water, and I have provided a bracket which may 10 be supported either on a plain surface, such as on the side of a fire truck, or on a plain board, or if desired the bracket may be supported upon a cylindrical standard such as a lamp post or pipe or the like which is often found upon the 15 roofs of buildings or adjacent the vicinity of the fire, and I have formed a bracket with a concaved recess between spaced feet so that a post or pipe may be received in this recess or the feet may be bolted to a plain surface to rigidly support the 20 bracket with its parts in the desired spaced relation to receive the turret standpipe which has cooperating portions formed thereon to hold it in the desired position in the bracket which portions are so constructed that the standpipe may be 25 released, taken from the bracket and moved about from place to place as desired.

With reference to the drawings, 16 designates the body of the turret standpipe, which has so-called "Siamese" inlet openings at one end consisting of three hose pipe connections 17, 18 and 19 while the opposite end of the body is turned upwardly as at 20 to which end a head 21 is 30 swivelly secured having the usual Y-form with a nozzle 22 secured thereto thru the connecting 35 member 23. A shut off valve 24 is located in the member 23 and provided with a handle member 25 for manual manipulation.

A pair of legs 26 project from the body adjacent its inlet end with spurs 27 at their ends while each leg has an opening 28 therein to receive a pin or the like on the bracket. A front plate 30 with a hole 31 therein is located adjacent the opposite or outlet end of the body for cooperation with the bracket and a pair of arms 32 are 45 pivotally mounted by a pin 33 from the end of which project legs 29 with spurs 29a thereon.

The turret standpipe thus formed is supported in a bracket consisting of a part 35 for the inlet end of the standpipe and a part 36 for engagement adjacent the outlet end thereof both of which are secured to the same support.

50 The bracket part 35 has a pair of pins or detents 37 extending therefrom which are received in the openings 28 in the legs 26 of the stand-

pipe to support and hold this portion in engagement therewith. The other part of the bracket, 36, is provided with spaced portions 38 having recesses 39 to receive the spurs 29a of the body, 5 and a ledge 40 to receive the under surface of the front plate 30 which is held in engagement with the body by a pin 42 slidably mounted in a cylindrical extension 41 to extend into the opening 31 on the body. This pin has an abutment 10 43 against which spring 44 acts to force it into said opening with a handle 45 for withdrawing it from engagement with the hole 31 to permit removal of the portable standpipe when desired.

It will be apparent that in positioning the 15 standpipe in the bracket the openings 28 are first placed over pins 37 and the forward part of the bracket swung or dropped down onto the ledge 40 at the same time withdrawing the pin 45 after which the pin may be released to be 20 forced by the spring into the opening 31 and hold the standpipe in position.

In the modifications shown a different construction of standpipe is provided which has a 25 pair of Siamese inlet openings 46 and 47 at one end of the body while the Y-head is swiveled by a suitable connection 48 to the other end of the body to revolve about an axis in line therewith.

The legs 26 are provided on this modification 30 with spurs 27 as before, and receive the pins 37 on one part 49 of a slightly modified form of bracket from that shown in Fig. 4.

The outlet end of the pipe, however, being differently shaped than that shown in Figs. 1 to 35 3, is clamped in the bracket part 50 by means of a split band having its upper half 51 hinged as at 52 to swing over a suitable cylindrical portion 53 of the body and be locked in this portion by means of the pin 54 and oblong head 55 and handle 56. The standpipe is thus secured 40 in this position while permitting the head 21 to have a bearing and to swivel while secured in the bracket to vary the stream of water as desired.

In some instances, however, the bracket part 45 50 may be so positioned as to clamp the body 16 inwardly from the swivel head 48 as illustrated in Fig. 13, in which case the clamp may be formed sufficiently tight so that a bearing need not be formed for the swivel of the head 21 in the bracket.

50 It is of course understood that where swiveling takes place that the cylindrical surface 53 will be finished in order to facilitate the rotation or swivel action of the head of the turret standpipe.

55 The brackets which I have illustrated each has its parts 35, 36 and 49, 50 so constructed as to form a pair of spaced feet 57, 58 and 59, 60 separated by an arc-shaped recess capable of receiving a lamp post, pipe or other suitable cylindrical 60 support 61, as illustrated in Fig. 14, to which it may be clamped by the part 62 and suitable bolts 63 to support the turret standpipe in a vertical position.

65 As shown in Figures 1 and 3, pins 64 are provided in the front plate 30, each of the same general construction as the pin shown in Figure 6, the ends of these pins (not shown) cooperating with spaced openings 65 in quadrants 66 secured to or integral with the legs 32, to releasably lock the legs in both folded and unfolded position.

70 It will be apparent that I have provided a bracket for a portable turret standpipe which has certain portions thereon to cooperate with the bracket such that the standpipe may be easily 75 and quickly positioned on or removed from the

bracket as desired and yet may be manipulated by a rotary movement of its swivel head and the nozzle in the head while in clamped position in the bracket.

The foregoing description is directed solely towards the construction illustrated, but I desire it to be understood that I reserve the privilege of resorting to all the mechanical changes to which the device is susceptible, the invention being defined and limited only by the terms of the appended claims. 5

I claim:

1. In a fire fighting apparatus, in combination, a turret standpipe for fire hose, a supporting bracket having spaced portions, cooperating recess and detent means respectively positioned on said standpipe and one portion of said bracket for mounting the standpipe thereon, and means on the other bracket portion for releasably locking said cooperating means in engagement. 15 20

2. In a fire fighting apparatus, in combination, a turret standpipe for fire hose, a supporting bracket having spaced portions, cooperating recess and detent means respectively positioned on said standpipe and on one portion of said bracket for mounting the standpipe thereon, and means on the other bracket portion for releasably locking said cooperating means in engagement, said bracket portions having spaced feet with arc-shaped recesses between whereby the bracket 25 30 may be supported on a plain surface or on a curved post or pipe.

3. In combination, a turret standpipe having a portion projecting therefrom with an opening therein, a bracket mounting therefor comprising spaced parts, a pin extending from one part to extend into said opening, and the other part having means to engage a remote portion of said standpipe to lock the projecting portion in engagement with said pin. 35 40

4. In combination, a turret standpipe having spaced portions projecting therefrom with openings therein, a bracket mounting therefor comprising spaced parts, pins extending from one part to extend into said openings in said portions, and means on the other part to engage a remote portion of said standpipe to lock the projecting portions in engagement with said pins. 45

5. In combination, a turret standpipe having a portion projecting therefrom with openings therein, a bracket mounting therefor comprising spaced parts, pins extending from one part to extend into said openings, and means on the other part to engage a remote portion of said standpipe to lock the projecting portion in engagement with said pins, said bracket parts having spaced feet with arc-shaped portions between whereby the bracket may be supported on a plain surface or on a curved post or pipe. 50 55

6. In combination, a turret standpipe having spaced portions projecting therefrom with openings therein, a bracket mounting therefor comprising spaced parts, pins extending from one part to extend into said openings in said portions, the other part having a rest for a remote portion of said standpipe, and a resilient detent on said other part for engaging said standpipe to lock said spaced portions in said bracket. 65

7. In combination with a turret standpipe having portions projecting therefrom with openings therein and spaced spurs positioned at a point remote therefrom, a bracket mounting therefor comprising spaced parts, spaced pins extending from one part of said bracket to extend into said openings, the other part having recesses to re- 70 75

ceive said spurs, and means to hold said standpipe in engagement with said bracket.

8. In combination with a turret standpipe having portions projecting therefrom with openings therein and spaced spurs positioned at a point remote therefrom, a bracket mounting therefor comprising spaced parts, spaced pins extending from one part to extend into said openings, the other part having recesses to receive said spurs, said standpipe having an additional opening and a resiliently mounted pin to engage said additional opening to lock the standpipe in engagement with said bracket.

9. In a fire fighting apparatus, a bracket support, a pipe having a horizontal branch to rest on said bracket and an elbow, a nozzle mounted on the elbow, collapsible legs carried by said pipe having an unfolded position such that when said pipe is placed with its horizontal branch on the ground they serve in cooperation therewith to hold said elbow upright, means for retaining said legs in folded position, said legs having a portion

which bears on the ground when the pipe is removed from the bracket support and on said support when the pipe is positioned thereon and quick detachable clamping means for securing said pipe to its support.

10. In a fire fighting apparatus, a bracket support, a pipe having a horizontal branch to rest on said bracket and an elbow, a nozzle mounted on the elbow, gate-like legs pivoted at one end to the pipe adjacent said elbow and adapted to be swung outwardly therefrom to unfolded position such that when said pipe is placed with its horizontal portion on the ground they serve in cooperation therewith to hold said elbow upright, means for retaining said legs in folded position, said legs having a portion which bears on the ground when the pipe is removed from the bracket support and on said support when the pipe is positioned thereon and quick detachable clamping means for securing said pipe to its support.
